COIN HANDLING MACHINE

Alfred Charles Otto Bock, Brooklyn, N. Y., assignor to Sattley Company, Detroit, Mich., a corporation of Michigan

Application November 28, 1931
Serial No. 577,825

8 Claims. (Cl. 133—3)

This invention relates to coin-handling machines and is concerned more particularly with a novel machine which receives miscellaneous coins, sorts them by denomination, counts the coins of each denomination separately, and discharges the coins separately into receptacles, one for each denomination.

At the present time there are numerous coin sorting and counting machines on the market but most of these machines are large, complicated, and expensive so that many small business organizations, churches, and the like, which have use for such a machine, are unable to afford the investment required. In these machines as commonly constructed there is a receptacle for the miscellaneous coins and a pickup plate by which the coins are removed one by one from the mass of loose coins in the receptacle. Usually the pickup plate has the form of a rotary disc which turns about an axis slightly inclined to the horizontal, and the coins picked up in pockets or recesses in the disc are discharged therefrom into another rotary element in which the sorting or classifying operation takes place. This sorting element frequently has a form known in the art as a turret and is a short cylinder rotatable upon a vertical axis and provided with radial slots. The turret and pickup plate are synchronized so that at the proper instant in their rotation the coins are discharged from the pockets of the pickup plate and each coin drops into one of the slots in the turret. The turret slots are of decreasing width in a downward direction and, as the coins enter the slots, they come to rest at different points in the slots determined by their size. Thereafter at the proper time the coins are separately discharged from the slots according to their denominations.

Machines of the construction above described have been developed in various forms and in general operate satisfactorily, although difficulties have been encountered due to jamming of the coins as they enter the turret. However, these machines are complicated and their cost is high, because so many of the parts require costly machining operations.

The present invention is accordingly directed to the provision of a novel coin sorting and counting machine which is of simple construction and can be made at low cost. By reason of its simplicity, the machine is highly efficient in operation and functions for long periods without the occurrence of jams which require that the machine be stopped and the jammed coins removed.

In the new machine I dispense entirely with

a turret or other separate classifying element and instead I employ a pickup plate which is provided on one face with recesses by which individual coins can be picked up from a loose mass, and on the other with classifying slots. These slots are formed in the flat back face of the plate and extend in a generally inward direction, the slots having a decreasing width toward their inner ends. Each slot is in communication at its outer end through the plate with one of the pickup recesses and in the rotation of the plate, a coin is picked up in each recess and then, at one point in the travel of the coin, it is passed through the plate to its rear face and enters one of the slots. As the rotation of the plate continues, the coin in the slot moves down through the latter to a position determined by the size of the coin. The coins are thus classified, with the coins of separate denomination occupying positions on the rear face of the plate at varying distances from the run thereof. After the coins have thus been classified, they are counted by suitable means and discharged into separate denominational receptacles provided for the purpose.

For a better understanding of the invention reference may be had to the accompanying drawings, in which

Fig. 1 is a face view of the machine;
Fig. 2 is a sectional view on the line 2—2 of Fig. 1;

Fig. 3 is a fragmentary face view with parts removed, the angle from which the illustration is made being indicated by the line 3—3 of Fig. 1;
Figs. 4 and 5 are fragmentary sectional views on the lines 4—4 and 5—5, respectively, of Fig. 3;

Fig. 6 is a sectional view on the line 6—6 of Fig. 2;

Fig. 7 is a sectional view on the line 7—7 of Fig. 8, showing a portion of the rear face of the classifying plate;

Fig. 8 is a sectional view on the line 8—8 of Fig. 7; and

Fig. 9 is a sectional view on the line 9—9 of Fig. 8.

The new machine comprises a supporting plate 10 provided with a boss 11 in which is mounted a shaft 12 provided with a gear 13 meshing with a worm 14 on a shaft 15 provided with a pulley 16. The pulley 16 is driven by means of a motor 17 and belt 18, the motor being mounted on cross bars 19 extending between two upright frame members 20, which also support the plate 10 at their upper ends. The plate 10 lies with its face slightly inclined to the vertical and the shaft 12

100

105

110

extends through the plate at a slight angle to the horizontal.

A ring 21 is attached to the periphery of the plate 10 and a hopper plate 22 is secured to the ring near its lower edge. Mounted on the end of the shaft 12 and in contact with the face of the plate 10 is a pickup and classifying element 23. This element may be formed as a single plate but is more conveniently made up of a pickup disc 24 on the outer face of the element and a classifying plate on the under side, the disc and plate being secured together face to face. The element 23 may be mounted on the end of the shaft 12 in any convenient manner or the shaft may constitute an integral part of the element, as illustrated. Between the end of the boss 11 and the element 23 is a ball bearing 26 so that the element may be freely rotated by the motor.

20 The pickup disc or plate cooperates with the hopper plate 22 to form a receptacle for a loose mass of miscellaneous coins to be sorted and counted and the disc is provided with pickup recesses 27 preferably made by cutting away the edge of the disc as illustrated in Fig. 3. With the disc thus constructed, the movement of the disc relative to the mass of coins in the receptacle causes coins to be picked up in the recesses and carried out of the mass. The pickup plate is relatively thin and the coins in the recesses are supported therein by a ring 28 mounted between the ring 21 and the rim of the supporting plate 10, the ring 28 extending inwardly a sufficient distance so as to underlie the recesses. To prevent more than one coin from occupying any recess, a leaf spring 29 is mounted on the inner edge of the plate 21 at a point where the edge of the pickup plate is moving upwardly past the spring. The spring bears against the edges of the coins in the recesses and operates to force out the top coin if there are two in a recess.

The classifying plate 23 mounted on the underside of the pickup plate is formed with a plurality of classifying slots 30 shown more clearly in Figs. 6 and 7. These slots extend in a generally inward direction and they have a decreasing width inward. Their width decreases by steps so as to form shoulders 31 along one side thereof and the configuration of these slots is such that coins occupy different positions in the slots depending on the size of the coins, each denomination of coin occupying a definite position in the slot.

At its outer end, each slot would be in communication with one of the pickup recesses 27 but for the interposition of the supporting plate 28. That plate, however, is cut away at a place designated 32 where the pickup recesses are moving downwardly toward the mass of coins 60 in the hopper. Adjacent this point, a cover 33 extends inwardly from the ring 21, overlying the outer edge of the pickup plate and preventing coins from the mass from entering pickup recesses at the point where the plate 28 is cut away.

65 The rear surface of the classifying plate 25 is formed with a plurality of concentric channels 34, each of which crosses all of the slots 30 and these channels are arranged so that each one enters one of the divisions of the slots. Mounted in the supporting plate 10 near the top thereof are pivoted arms 35, each of which carries at one end a roller 36 which enters one of the concentric channels. The other end of each arm bears against a plunger 37 provided with a rack 70 38 actuating a gear 39 on the shaft of a counting

device 40. The several counting devices are all mounted in one housing 41 attached to the plate 10 at a convenient point and are provided with a resetting handle 42.

The supporting plate 10 is formed with a plurality of chutes 43, which lead downwardly and discharge separately into boxes 44, one for each denomination of coin, the chutes being of different sizes according to the denomination of the coins which are to pass through them. At the top of the group of chutes is a plate 45, the edge of which in part defines openings through plate 10, through which coins may be discharged from the classifying slots in the plate 24. The coins passing through these openings enter the chutes and fall downwardly into the separate coin boxes. The plate 45 is provided with prongs 46, one for each opening, and each prong enters one of the concentric channels 34 in the classifying plate. The opening to each chute is in registry with one of these channels and, therefore, with one subdivision of each slot.

In the operation of the machine, the loose coins to be sorted and counted are introduced into the receptacle formed by the hopper plate 22 and by the face of the combined pickup and classifying element 23. As the element rotates, individual coins enter the pickup recesses in the element and are carried upwardly from the mass and then downwardly and beneath the cover 33. In their movement to the cover the coins are supported in the recesses on the ring 28 but, beneath the cover, the ring is cut away so that each coin falls through the recess and into a classifying slot in contact with the surface of a portion of the supporting plate 10. Upon continued rotation of the element 23, the coins travel upwardly as shown in Fig. 3 until a point is reached where each coin slides down in its slot by gravity to assume a position of rest determined by its size. The slots are not radially disposed but are at an angle to radii so that the coins move down the slots sooner than would be the case if the slots were radial.

As the separate coins, one in each slot, are carried along, they pass beneath the rollers on the levers 35 and when a coin lifts the roller end of the lever, the lever operates its counting mechanism. Just beyond the counting device, the coins are picked out of the slots by the prongs 48 and pass through openings into the chutes 43. These chutes lead to the separate coin boxes, one for each denomination of coins being handled.

While the construction has been described as including a picking up and classifying element 23 made up of two parts, the pickup disc 24 and the classifying plate 25, it will be evident that those parts could be made integral without departing from the principles of the invention. It is more convenient to make the parts separate and secure them together face to face, in which position they function as a single element.

It will be observed that in the new machine, the coins are picked up and classified by the same moving element and the coins are in contact with this element at all times from the time that they are picked up until they are discharged into their separate chutes. The coins lie flat at all times and in their classifying movement along the slots they are supported on their faces instead of on their edges. By using a single element for the combined purpose of picking up and classifying the coins, the construction of the machine is greatly simplified and by reason of the small extent of movement of the coins relative to the

pickup and classifying element from the time the coins are picked up until they are discharged, there is little opportunity for the coins becoming jammed.

5 In prior machines of the turret type, coins are picked up and then transferred into the turret, with the coins not in contact with supporting surfaces at all times during their movement. The coins are thus not fully guided and jamming 10 frequently occurs. In my machine, each coin is supported on its face from the time the coin is removed from the hopper until the instant of discharge and the complete guidance and support afforded the coins reduce the possibility of their becoming wedged or leaving the paths of travel 15 which they are intended to take.

My machine is so constructed that only one coin can be picked up in each recess and that coin travels through an arc of approximately 540° in 20 the machine. Throughout the first half of this movement, the coin is in a pickup recess and just before this coin would again enter the mass in the receptacle, it is passed to the rear face of the pickup and classifying element and enters one 25 of the classifying slots. The coin remains at rest in this slot through a movement of approximately 180° and then on further movement, the coin begins to move inwardly along the slot to assume a position of rest determined by its size. The 30 coin slides along a flat surface in contact with a smooth edge of the slot and eventually contacts with a shoulder on the other edge, this shoulder supporting the coin in its proper position determined by its denomination. While the 35 coin is advancing along its path with the plate after such classification, it is counted and then discharged into the chute which delivers it into its appropriate box.

The machine is of simple, relatively inexpensive construction and does not include the large 40 number of highly machined parts customarily present in such devices. It functions efficiently and rapidly and may be used for long periods of time without becoming jammed or requiring 45 any attention.

What I claim is:

1. In a coin sorting machine, a plate mounted for rotation and having coin pick-up recesses in one face, classifying slots in the other face, each 50 slot communicating near one end with a recess and decreasing in width in successive steps toward the center of said plate, and concentric slots intersecting said classifying slots, each of the concentric slots registering with one of the 55 steps in each classifying slot.

2. In a machine for handling coins, the combination of a receptacle for a mass of unsorted coins, a plate mounted for rotation and having one face forming a wall of the receptacle, said 60 face being formed with pick-up recesses, each adapted to receive one coin at a time with said coin lying with its faces parallel to the face of said plate, classifying slots in the other face of said plate, each slot communicating at its outer 65 end with a recess and extending inwardly from the periphery of said plate, each slot having a flat bottom lying parallel to the plane of said plate and being adapted to receive a coin from said communicating recess, said slot being of 70 gradually decreasing width inwardly from said periphery, means engaging one face of each coin in a slot and supporting said coin therein while permitting it to move inwardly along said slot, concentric slots in said plate intersecting said 75 classifying slots, and means entering said con-

centric slots and actuated by said coins for counting them.

3. In a machine for handling coins, the combination of a receptacle for a mass of unsorted coins, a plate mounted for rotation and having one face forming a wall of the receptacle, said face being formed with pick-up recesses, each adapted to receive one coin at a time with said coin lying with its faces parallel to the face of said plate, classifying slots in the other face of said plate, each slot communicating at its outer 80 end with a recess and extending inwardly with a gradually decreasing width from the periphery of said plate, each slot having a flat bottom lying parallel to the plane of the plate and being adapted to receive a coin from said communicating recess, means engaging one face of each coin in a slot and supporting said coin therein while permitting it to move inwardly along said slot, concentric slots formed in the 85 face of the plate in which said classifying slots are formed, said concentric slots intersecting said classifying slots, and means entering said concentric slots for removing the classified coins 90 from said classifying slots.

4. In a machine for handling coins, the combination of a receptacle for a mass of unsorted coins, a plate mounted for rotation and having one face forming a wall of the receptacle and in contact with said coins, said face being formed 100 with pick-up recesses, each adapted to receive one coin at a time with said coin lying with its faces parallel to the face of said plate, classifying slots in the other face of said plate extending inward from the periphery thereof, each slot 105 communicating at its outer end with a recess and being of gradually decreasing width inward from said periphery, each slot having a flat bottom parallel to the plane of said plate and being adapted to receive a coin from said communicating recess, a stationary plate having a face 110 engaging one face of each coin in a slot and supporting said coin while permitting it to move inwardly along said slot as said first plate rotates, concentric slots in said other face of the rotating 115 plate intersecting said classifying slots, and means entering said concentric slots and actuated by the coins in said classifying slots for counting them.

5. In a machine for handling coins, the combination of a receptacle for a mass of unsorted coins, a plate mounted for rotation and having one face forming a wall of said receptacle and in contact with said coins, said plate being formed with pick-up recesses extending through 125 it and open at said face, each pick-up recess being adapted to receive one coin at a time, a plate underlying said recesses and supporting the coins therein with their faces parallel to the face of said plate, classifying slots in the other face of 130 said plate extending inwardly from the periphery thereof, each slot intersecting one of said recesses at its outer end and being of gradually decreasing width inwardly from said periphery, each slot having a flat bottom parallel to the 135 plane of said plate and being adapted to receive a coin from said recess which it intersects, a plate beneath said slots having a face engaging one face of each coin in a slot and supporting said coin while permitting it to move inwardly 140 along said slot, concentric slots in said other face of the rotating plate intersecting said classifying slots, and means entering said concentric slots and actuated by said coins in said classifying 145 slots for counting them.

6. In a machine for handling coins, the combination of a receptacle for a mass of unsorted coins, a plate mounted for rotation and having one face forming a wall of said receptacle and in contact with said coins, said plate being formed with pick-up recesses extending through it and open at said face, each pick-up recess being adapted to receive one coin at a time, a plate underlying said recesses and supporting the coins therein with their faces parallel to the face of said plate, classifying slots in the other face of said plate extending inwardly from the periphery thereof, each slot intersecting one of said recesses at its outer end and being of gradually decreasing width inwardly from said periphery, each slot having a flat bottom parallel to the plane of said plate and being adapted to receive a coin from said recess which intersects, a plate beneath said slots having a face engaging one face of each coin in a slot and supporting said coin while permitting it to move inwardly along said slot in a plane parallel to the face of said rotating plate, concentric slots formed in said other face of the rotating plate and intersecting said classifying slots, and means entering the concentric slots for removing the classified coins from said classifying slots. 80
- 10 7. In a machine for handling coins, the combination of a receptacle for unsorted coins, a plate mounted for rotation and having one face forming a wall of the receptacle and in contact with said coins, said plate having pick-up recesses extending through it, each recess being adapted to receive one coin at a time, a stationary plate cooperating with said rotating plate to support the coins in said recesses, said coins lying in said recesses with their faces parallel to the plane of said rotating plate, and said stationary plate having an opening through which said coins may move out of said recesses, classifying slots formed in the other face of said rotating plate and extending inwardly from the periphery thereof with a gradually decreasing width, each slot at its outer end intersecting a recess and having a flat bottom parallel to the plane of said rotating plate, a plate having a face engaging one face of each coin in a slot and supporting said coin while permitting it to move inwardly along said slot in a plane parallel to the face of said rotating plate, concentric slots formed in said other face of the rotating plate and intersecting said classifying slots, and means entering the concentric slots for removing the classified coins from said classifying slots and discharging them separately. 85
- 15 8. In a coin-sorting machine, a plate mounted for rotation and having coin pick-up recesses in one face and classifying slots in the other face, the bottoms of said classifying slots lying parallel to the plane of said plate and said slots extending inwardly from the periphery of said plate with a gradually decreasing width, each classifying slot intersecting a pick-up recess, and concentric slots formed in said other face of said plate and intersecting said classifying slots. 90
